INTERCOMMUNICATING TELEPHONE AND
SIGNALING SYSTEMClarence E. Lomax, Oak Park, Ill., assignor to
Associated Electric Laboratories, Inc., Chicago,
Ill., a corporation of Delaware

Application July 13, 1933, Serial No. 680,169

12 Claims. (Cl. 179—32)

The present invention relates in general to telephone and signal systems and specifically to small intercommunicating telephone or signal systems adaptable for use in hotels, schools, and other institutions. The principal object of the invention is the provision of a more inexpensive and simpler system which will furnish local communication service in a reliable manner.

According to the system of the invention, a master station is provided, together with a number of extension stations, all of which are connected together to a common talking line circuit. The extension stations are arranged to call the master station only, while the master station can call any one or a number of the extension stations.

In previous systems of the above character it was customary to provide a key at each extension station in order to signal the master station, while the master station was arranged with a separate key for each of the extension telephones in the system. This required a large number of keys at the master station with the consequent large number of conductors. It is an object of this invention to eliminate the signaling keys at the extension stations and greatly reduce the number required at the master station. In accordance with this object, a particular feature of the invention resides in providing a double key operation at the master station in order to select any one of a number of extension stations. One of the keys, termed the "group selecting" key, is arranged upon actuation to select a group of extension stations of which the desired station is one, and another key, termed a "units selecting" key, connects with the particular extension station of the group selected by the "group" key.

The invention is not necessarily limited to systems involving telephonic communication but is applicable likewise to signaling systems for hotels, schools, etc., where buzzers, lamps, or bells are only provided, and by means of the keys and circuit arrangement according to the invention any signal at any location or any group of signals may be actuated to impart information to persons, which information may be in the form of a code, if desired.

In the system about to be described a maximum of one-hundred extension stations and one master station is contemplated. The extension stations may therefore be numbered or arranged on a decimal basis and divided into ten different groups, each with a separate group selecting key at the master station, while only a single group

of units selecting keys numbered from 1 to 10 is provided.

A further object of the invention is to provide means for simultaneously signaling a group of extension stations and in accordance with this object a "group ringing" key is provided which, upon actuation, will signal an entire group of extension stations at once depending upon which group selecting key is operated.

Other objects and features of the invention involving certain circuit arrangements and operations will be readily apparent from the detailed description which, together with the drawings, discloses the invention in its preferred form together with certain modifications.

In the drawings, Fig. 1 illustrates schematically an intercommunicating system showing the nature and principles of a preferred embodiment of the invention; Fig. 2 is a modification of the system shown in Fig. 1 wherein a saving in wiring is effected; while Fig. 3 illustrates a modification wherein a rotary switch is substituted for the units selecting key shown in Fig. 1.

Referring now to Fig. 1, the drawings illustrate a small intercommunicating or private telephone system comprising a master station MS and a number of extension telephone stations Nos. 20, 46, and 48. Only a few extension telephones have been shown for the purpose of illustration, it being understood that the system to be described comprises a maximum number of one-hundred extension telephones. In the layout of an example of the type of system or arrangement in which this system is applicable, it is assumed that the master station MS is located in a building on a particular floor while the extension stations Nos. 46 and 48 are located on another floor of the same building and the station No. 20 on still another floor. These extensions are arranged on their particular floors with other similar stations with which they form a part of a particular group.

A common talking line circuit 11 and 12 extends from the master station MS in multiple to all of the floors of the building and also in multiple to all of the extension telephones of the group on each particular floor. Extension stations Nos. 46 and 48 and others in the same group are connected to common talking line 13 and 14, while station No. 20 and its associated stations in the group are connected to common talking line 15 and 16.

Associated with the master station MS and suitably mounted in a cabinet in close proximity to the station are a number of manually oper-

ated keys or push buttons. In a hundred-station system these keys will consist of ten "group selecting" keys each of which corresponds to and is associated with a particular group of extension stations, for example, a group on each floor of the building. A group of "units selecting" keys numbered 1 to 10 is connected to conductors 1 to 10 which are in multiple with and common to all the "group selecting" keys. An additional key, termed a "group ringing" key, is multipled to the units selecting keys and to all the group selecting keys over common conductors 1 to 10.

It will be observed that station No. 20 is provided with a buzzer or signal 71 which is connected over signaling conductor 19 with the contacts 35 of group selecting key 20. Station No. 48 has its signal 72 connected over conductor 18 with contacts 33 of group selecting key 40, while extension station No. 46 has its signal 73 connected over signaling conductor 17 with contact springs 34 of group selecting key 40. In the group of stations controlled by group selecting key 20, the signals of all stations Nos. 21 to 28 in the group are connected to the contacts of this key. In a similar manner the remaining contacts of group selecting key 40 are connected to the signals of the remaining extension stations of this group. From the foregoing, it is seen that each group selecting key, of which there are ten, has a conductor extending to the buzzer of signaling device of the extension telephone in its particular group. The operation of any group selecting key will therefore prepare the circuits for all the signals of all the extension telephones with which the key is associated. The operation of any one of the units selecting keys numbered 1 to 10 will close a circuit from battery through the particular operated units selecting key, over the multiple connections 1 to 10 depending upon which units key is operated, and then through the particular contact springs of the operated group selecting key to the signal of the wanted extension station.

Connected in multiple to the common conductors 1 to 10 is the group ringing key which, upon being actuated, connects the battery through all of its contacts directly onto the common conductors 1 to 10 and then through the contact springs of any one or a number of group selecting keys which may be operated, to the signals of all of an associated group of extension stations.

It will be assumed now, for example, that the master station MS desires to call the extension station No. 20. The operator thereupon first actuates the group selecting key 20 which prepares the signaling circuits of all the telephones in that particular group of which extension telephone No. 20 is one. The group selecting keys are all arranged so that they will remain locked in their operated positions. The operator then operates the units selecting key No. 10. This extends the battery circuit through key No. 10, common conductor 10, contact springs 35 of group selecting key 20, signaling conductor 19, signal 71, switchhook contacts 7, common talking lines 16 and 12, through the lower winding of relay 20 to ground. Due to the relatively high resistance of the signal 71, the relay 20 does not operate. The signal, however, operates and attracts the attention of the person assigned to extension station No. 20.

In case the master station MS desires to signal the extension station No. 48, the group selecting key 40 would first be operated and then the units selecting key No. 8 to close the signal circuit from

battery, contacts of units selecting key 8, common conductor 8, contact 33 of group selecting key 40, conductor 18 to the signal 72. In a similar manner the extension station No. 46 would be selected in the group 40 and then the units key 6 operated. Units keys 1 to 10 are of the non-locking type and may be manipulated by the operator at the master station MS in any manner to actuate the signal of the called extension station. In the above manner as described any one of the hundred stations in the system may be similarly signaled by merely actuating the group selecting key to select the particular group of which the desired station is one while any one of the units selecting keys Nos. 1 to 10 are actuated to directly operate the signal of the desired station. This obviates the necessity of providing separate keys for each extension station in the system, and in the example described of one-hundred stations only ten group selecting keys would be required while only one group of units selecting keys is necessary. Any particular group of extension stations may be signaled by the group ringing key depending upon which group selecting key is operated. It will also be appreciated that any number of group selecting keys may be operated to operate more than one group of signal devices at the associated extension stations.

When any particular extension station responds to the actuation of his calling signal, for example, that of station No. 20, the receiver 74 is removed from the switchhook, resulting in the disconnection of the signal device 71 at the switchhook contacts 7. At the same time the switchhook contacts 75 close, thereby extending the circuit of the extension telephone through its transmitter 76, receiver 74, switchhook contacts 75, across the common line conductors 15 and 16 which extend over common talking conductors 11 and 12 through the upper and lower windings of relay 20 to ground and battery, respectively. Relay 20 energizes and at its front contact and armature 21 projects ground to armature 31 and its back contact, armature 41 and its back contact, through the signal such as buzzer 60 at the master station MS to battery, thereby notifying the operator at the master station MS that the called extension station has responded. It will be understood, of course, that in certain instances the operator at the master station may have his receiver removed from the hook and listen in before the desired station answers and in this case the signal 60 would not operate. In any case, however, response at 55 the master station closes a loop circuit extending through the transmitter 61, receiver 62, switchhook contacts 63, through the upper and lower windings of relay 39 to battery and ground, respectively. Relay 39, upon operating, opens its armature 31 from its back contact, thereby disconnecting the circuit of signal device 60. The master station MS may now engage in conversation with the extension station No. 20, talking current being furnished for the extension station through the windings of relay 20 while the master station receives its talking current from relay 39 and its winding. The condensers 22 and 23 in the lines 11 and 12 separate the two sources of potential.

It will be appreciated that the system of selection pointed out is extremely flexible, for example, the operator at the master station MS may select any one particular extension station, any group of extension stations, or any number of

stations simultaneously in different groups for the purpose of engaging in a conference calling circuit. By the operation of any one or a number of group selecting keys and also by simultaneously operating any one or a number of the units selecting keys any particular desired number of extension stations may be signaled simultaneously and each one, upon responding to its signal, is automatically connected across the common talking lines 11 and 12 with the telephone of the master station MS.

In certain instances it may be desirable for two or more extension telephones to be connected together for communication purposes, and this is accomplished by one of the stations first signaling the master station MS in a manner as has been pointed out and then the master station by means of the group selecting and units selecting keys signal the other extension station with which the first station desires to be connected. After both stations have been connected to the common talking line 11 and 12 the master station MS may retire from the connection, and in order to prevent the signaling device 60 of the master station MS from being actuated while the two extension stations are connected to the common talking line 11 and 12, a holding key HK is provided. It will be seen that when the master station MS has the receiver 62 placed on the switchhook 63 the relay 20 is in a deenergized condition and closes its armature 31 on its back contact. This would ordinarily close a circuit for the signal device 60 through ground on front contact of armature 21 of relay 20 which is now operated, through the armature 41 and its back contact of relay 40. In order to prevent the unnecessary operation of the signal device 60 under these conditions, the operator at master station MS momentarily operates the holding key HK which closes a circuit from ground at the key through the winding of relay 40 to battery. Relay 40, upon operating, closes a locking circuit for itself through its front contact and armature 41, back contact and armature 31, to ground on the front contact of armature 21 on relay 20. Relay 40 therefore is held operated under control of relay 20 so that as long as the extension stations remain upon the line the signal 60 will not be operated. However, when the common talking line 11 and 12 is cleared relay 20 deenergizes and opens the circuit for locking relay 40 so that the signal 60 is again placed in circuit under control of relay 20 so that other stations which may desire to signal the master station MS can do so.

It will be appreciated that in the layout of the system described wherein a different group of telephone extension stations is located on different floors of a building it is necessary to extend ten conductors from each group selecting key to the particular floor or location of each group of telephones with which it is associated. This entails the running of one-hundred conductors from the master station throughout the system.

Referring now to the modification shown in Fig. 2 it is contemplated in this instance to provide a layout similar to that disclosed in Fig. 1 wherein a master station is provided and groups of extension stations are provided on each floor of an institution, all connected together over a common talking circuit 53 and 59. Group selecting keys and units selecting keys are likewise provided, but in order to effect a considerable saving in the wiring a single conductor from each of the group selecting keys 1 to 10 is extended to an in-

dividual relay located on the same floor with its associated group of extension stations. For example, group selecting key No. 1 is directly connected with relay 52, while group selecting key 8 is connected to relay 53. The units selecting keys are connected directly in multiple through the contact springs extending to each of the relays connected to the group selecting keys on each floor. In this matter if the master station MS desires to connect with extension station No. 76, for example, the group selecting key 1 is actuated at the master station, extending ground to the contacts of the key 1 to relay 52 to battery. Relay 52, upon operating, closes all its armatures on its front contacts, including contact No. 55. The group selecting keys, being of the locking type, remain operated. The operator then actuates the units selecting key No. 6, thereby closing battery through the contacts of key 6, armature and front contact 55 of relay 52, through the signaling device 62 to ground at the extension station 76. The extension station, upon responding to the signal, is connected directly to the common talking conductors 58 and 59, thereby in the manner described in connection with Fig. 1 actuating the signal 60 at the master station to indicate his response. The other stations in the system may be called in a similar manner or any group of them may be signaled by manipulation of the group selecting keys of any one or a number of the units selecting keys. In this connection it may also be pointed out that the group ringing key has not been shown in this modification, although it may be connected directly to the conductors connected to the units selecting keys for signaling any desired group of extension stations.

While the invention has been more or less described as being applied in connection with a telephone system, it will be appreciated that in certain institutions, such as small hotels or small factories, telephone communication is not always desirable or too expensive, but some sort of signaling system is required. Telephones may therefore be dispensed with and only the signaling devices may be employed. The operator at a particular master station may operate the group selecting and units selecting keys to signal any signaling station or signal device or any group of devices to summon a particular person in close proximity to such devices. By proper manipulation of the units selecting keys in accordance with a prearranged code the signal devices may be operated to respond to this code to convey intelligence to any person in proximity thereto.

Fig. 3 discloses a modification of the signaling arrangement shown in Figs. 1 and 2 in that a units selecting switch is provided in place of the units selecting keys. This switch may take the form of a circular row of contacts 1 to 10 over which a manually operated wiper may be rotated to select any one of the common conductors 1 to 10 to directly operate the signal devices which have been previously selected or prepared by the group selecting keys which are connected to the common conductors 1 to 10. By employing a rotary switch for the units selector a simpler device than the group of units selecting keys is provided.

From the foregoing description it will be seen that the invention considerably reduces the amount of apparatus necessary at a master station and greatly simplifies the operation of selecting a particular extension, thereby rendering a system of this type a great deal more efficient and

inexpensive than similar systems have been previously.

What is claimed is:

1. In a telephone system, extension telephone stations arranged in groups on a talking line, a master station, group selecting keys, one for each of said groups of extension stations at said master station, units selecting keys at said master station common to said group selecting keys, 5 the actuation of one of said group selecting keys selecting the group of extension stations containing the station desired by the master station, while the actuation of a certain one of the units selecting keys selects the desired extension station 10 in the group selected by said group selecting key, and means for connecting said selected station and said master station together on said talking line.
2. In a telephone system, extension telephone stations arranged in groups, a call signal at each of said stations, a master station, a common talking circuit connecting said master station and all of said extension stations, group selecting keys at said master station one for each group 15 of extension stations, units selecting keys at said master station, the operation of one of said group selecting keys selecting a group of call signals including the signal of the extension station which the master station desires to establish connection with, while the operation of one of said units selecting keys directly operates the call signal of the particular extension station in the selected group, and means for connecting said selected extension station with said master station over said common talking circuit and disconnecting 20 said call signal from operation.
3. In a telephone system, groups of signal stations, a separate group selecting key for each of said groups of stations, a units selecting key common to all of said group keys for signaling the particular station in the group selected by said group key, and a signaling key common to said group and units keys for signaling a group of stations depending on which group key is 25 operated.
4. In a signaling system, stations arranged in groups, a call signal for each station, a group selecting key for each group of stations for selecting the group of call signals associated with said group key, a units group of keys for operating the particular call signal of the group of call signals selected, and a group signaling key for operating the group of call signals selected by any operated group selecting key.
5. In a telephone system, telephone stations arranged in groups, a call signal for each station, a group selecting key for each group of stations for selecting the same, the call signal from each station of a group being connected to its associated group selecting key, a units selecting key common to all group selecting keys for operating a particular call signal in the group connected to any group selecting key, and a group signaling key common to all of said group selecting keys for operating all of the call signals in a group depending on which group selecting key is operated.
6. In a telephone system, telephone stations arranged in groups, a call signal for each station, a group selecting key for each group of stations for selecting the same, the call signal from each station of a group being connected to its associated group selecting key, a units selecting key common to all group selecting keys for operating a particular call signal in the group

connected to any group selecting key, a group signaling key common to all of said group selecting keys for operating all of the call signals in a group depending on which group selecting key is operated, and a common talking circuit 5 for all signaled telephone stations to connect to for communication purposes.

7. In a telephone system, telephone stations arranged in groups, a call signal for each station, a group selecting key for each group of stations 10 for selecting the same, the call signal from each station of a group being connected to its associated group selecting key, a units selecting key common to all group selecting keys for operating a particular call signal in the group connected to 15 any group selecting key, and a group signaling key common to all of said group selecting keys for operating all of the call signals in a group depending on which group selecting key is operated, and means at each telephone station for disconnecting its associated call signal from operation.

8. In a telephone system, extension telephones arranged in groups, each telephone having a signaling device, a master station having a signaling device, a group selecting key at said master station for selecting and preparing the circuit of the signal devices for a group of master stations, a units selecting group of keys at said master station for directly operating the particular signal prepared by said group selecting keys, means at 20 the desired extension station in response to actuation of a calling signal for operating the signal of the master station, and means at said master station for disconnecting its signal from operation.

9. In a telephone system, extension telephones arranged in groups, a signal at each extension station, a master station having a signal thereat, a group selecting key for preparing the circuit for the signal of a particular group of extension stations, a group of units selecting keys for directly operating the signals selected by the group selecting keys, means at the extension station in response to the actuation of its signal device for automatically operating the signal of the master 40 station, and means at said master station for either automatically or manually disconnecting its signal from operation.

10. In an intercommunicating telephone system, a group of extension stations each having a 50 signaling device therein, a master station connected over a common talking circuit with said extension stations, a signal at said master station, means at any of the extension stations for actuating the signal of the master station when it 55 is desired to establish a connection therewith over said common talking circuit, a holding key at said master station, means responsive to the actuation of the holding key for disconnecting the master station signal so that any other extension 60 stations may be connected together without signaling the master station.

11. In an intercommunicating telephone system, extension stations divided into groups, a master station, a common talking circuit extending to all of said extension stations and said master station, signals at each of said stations, a group selecting key for selecting a particular group of extension station signals, a station selecting key for directly operating a particular 70 extension station signal of the selected group, the removal of the receiver at the master station and the signaled extension station directly connecting said stations to said common talking circuit, a pair of relays in said talking circuit, one 75

of said relays feeding talking current to said extension station and the other relay to said master station, and means for separating said sources of talking current from each other.

- 5 12. In an intercommunicating telephone system, extension stations divided into groups, a master station, a common talking circuit extending to all of said extension stations and said master station, signals at each of said stations, a group selecting key for selecting a particular group of extension station signals, a station selecting key for directly operating a particular extension station signal of the selected group, the removal of the receiver at the master station and

the signaled extension station directly connecting said stations to said common talking circuit, a pair of relays in said talking circuit, one of said relays feeding talking current to said extension station and the other relay to said master station, means for separating said sources of talking current from each other, means controlled by the relay feeding talking current to the extension station for signaling the master station, and means controlled by the relay feeding talking current to the master station for disconnecting the master station signal. 10

CLARENCE E. LOMAX.
